UNDERGROUND STORAGE SYSTEM

Carl T. Brandt, Bartlesville, Okla., assignor to Phillips Petroleum Company, a corporation of Delaware

Application May 16, 1955, Serial No. 508,523

12 Claims. (Cl. 61—0.5)

This invention relates to underground storage systems. The constantly expanding production of liquefied petroleum gas has created a definite problem in providing suitable storage facilities for this material. Due to the high vapor pressure of LPG, liquefied petroleum gas, particularly propane, the cost of storage in surface equipment, such as steel tanks, becomes excessive due to the massive construction required to withstand the vapor pressure of the stored material in a safe manner. This problem looms especially large where it is necessary to store large quantities of such materials during the off-season. In addition to the expense involved, the use of steel tanks is often limited by shortages in production, especially during war-time conditions.

In order to overcome these difficulties, it has been proposed to store liquefied petroleum gas underground, as for example, in mined caverns. While this type of storage is cheaper than an equivalent capacity in steel tanks, it poses the problem of forming a gas-tight seal in the cavern entrance. The logical type of seal would appear to be a concrete block, poured so as to fill the cavern entrance, with the necessary piping extending through this block into the cavern. However, such a concrete block, even though waterproof, cannot always be depended upon to be impervious against the pressurized gases in the cavern. The present invention provides a means of insuring a gas-tight seal in the cavern entrance while still employing a concrete slab or other relatively cheap type of bulkhead.

It is an object of the invention to provide underground storage facilities of novel construction and arrangement, said facilities providing storage at a minimum unit cost.

It is a further object to provide such a system in which the cavern is an existing structure such as an abandoned tunnel.

It is a still further object to provide an underground storage system capable of storing volatile liquids without loss.

Figure 1 is a vertical section view, partially in elevation, of the underground storage system of this invention; and

Figure 2 is an enlarged vertical sectional view of the tunnel system.

Referring now to the drawings in detail, and particularly to Figure 1, the underground storage system of this invention includes one or more underground storage caverns, one of which is indicated by reference numeral 10. It will be understood that each cavern can consist of a large excavated region, as illustrated in Figure 1, or alternatively, the cavern can comprise a series of elongated individual storage chambers of cylindrical or rectangular cross section with the axis in a horizontal or vertical direction, as desired, all of the chambers defining the cavern communicating with a common tunnel leading to a central shaft in the manner hereinafter explained.

A tunnel 11 connects the cavern 10 with a shaft 12 extending to the surface. It will be understood that, where a plurality of caverns are utilized, each cavern can be connected to the central shaft by a separate, preferably horizontal, tunnel. One such additional tunnel is indicated by reference numeral 11a and it is connected to a

2

cavern, not shown, similar to the cavern 10. Each tunnel should be of sufficiently large cross sectional area to permit access thereto by workmen. In one specific embodiment, the shaft 12 is 260 feet deep and extends vertically.

In accordance with the invention, each tunnel incorporates a sealing structure, preferably disposed at the end of the tunnel remote from the shaft, to the end that liquid or vapor cannot leak from the caverns into the tunnels or shafts, even where the stored material is quite volatile and, therefore, develops a high vapor pressure. A suitable sealing structure is shown in connection with tunnel 11, this structure including a concrete wall or bulkhead 14, preferably formed from poured concrete and disposed in the tunnel at the cavern entrance. Between the shaft 10 and bulkhead 14 is a second bulkhead 15, preferably formed from poured concrete and substantially thicker than the other. In this manner, a chamber 16 is defined between the bulkheads 14, 15 which can be filled with a viscous substance, preferably drilling mud, which is immiscible with the stored product. The means of filling the chamber 16 is discussed later in connection with Figure 2. Exterior bulkhead 15 is built to withstand the total pressure exerted by the stored fluid in cavern 10. Interior bulkhead 14 is designed only to withstand the small pressure differential between the stored fluid and the sealing liquid.

A large tubular conduit or manway 20 extends through bulkheads 14 and 15, one end extending into and communicating with the cavern 10 and the outer end extending into the tunnel 11. This manway is open on the storage side but the outer end is closed and sealed by a flanged metal cap 21 bolted thereto. Line 22 connects the top of tank 26 with manway 20 through cap 21. Line 23 branches from line 22 and connects to the top of tank 25. The bases of tanks 25, 26 are connected through respective lines 27, 28 to the interior of seal chamber 16. Lines 27, 28 are filled with the same sealing liquid present in chamber 16; lines 22, 23 are filled with stored product. The interfaces of the two substances in tanks 25, 26 are indicated generally at 30, 31. Pipe 34 provides a direct connection between line 22 and the interior of chamber 16, check valve 33 being designed to permit only one-way flow, permitting gas to enter the seal chamber under conditions described later.

In further accordance with the invention, a filling and dispensing line 36 extends through the bulkheads 14, 15 and has one end 37 thereof disposed within the cavern 10. Preferably, the end 37 is elevated, as by providing supports 38, 38' beneath the line, and is slotted on its underside. In this manner, fluids are easily introduced into the line from the cavern or pass into the cavern through the line, and there is less chance for the end of the pipe to become clogged by rocks or other debris accumulating at the bottom of the cavern. If desired, additional perforations can be provided in a portion of the line which rests upon the floor of the cavern to allow removal of residual portions of stored material. Pump 40 permits the elevation of fluid from line 36 to the surface through line 41 extending up through shaft 12 into storage vessel 42.

It is evident that the aforesaid means provides for a substantial equalization of pressure in the storage cavern and adjacent chamber. However, the pressure of the drilling mud against bulkhead 14 will always exceed the opposing pressure of the stored product so long as the propane-mud interface in the equalizer tanks is higher than the top of the sealed chamber.

Figure 2 illustrates in somewhat greater detail the sealing system of the invention as applied to a tunnel, both ends of which are at the surface of the earth. In a typical embodiment, tunnel 10a is an abandoned railroad tunnel in a hill 49, supplied with storage fluid through line 39, and closed at each end by bulkheads 14, 14a and 15, 15a

of the type described in connection with Figure 1. The seal spaces 16, 16a are filled with a viscous fluid, preferably a drilling mud, as in Figure 1. As shown in the lefthand side of the figure, manway 20 connects through line 22 to tanks 25, 26 as in Figure 1 and safety valve 33 is likewise provided.

A mud recirculating and vent line 50, preferably a two-inch pipe, extends from the top of seal chamber 16 through bulkhead 15 and connects to the discharge of mud pump 52. A similar pipe 53 extends from the base of seal chamber 16 through bulkhead 15 to the pump 52 and to tank 26 forming an interface between the stored fluid and the sealing fluid at the level indicated. Line 54 branches from line 53 and connects to the base of tank 25 forming a similar interface therein. The operation of pump 52 maintains circulation of the mud from seal chamber 16 to the pump and back.

When mud is first pumped into chamber 16 it is admitted from pump 56 to line 53 on opening valve 58. It is thus pumped through line 53 into the base of chamber 16. Air displaced from chamber 16 is vented through line 50 by opening valve 61. Once chamber 16 is filled, valves 58 and 61 are closed and valve 60 opened. Pump 52 now draws mud through line 53 and returns it through line 50. When mud needs to be added to the system during normal storage, it is admitted through line 57 by opening valve 58 and operating pump 56.

It should be understood that the seal system at the other end of the tunnel, indicated generally by pipes extending through bulkheads 14a, 15a, is identical with that just described and, hence, need not be described further.

Conduits 22, 23 are connected to blowdown lines 62, 63, respectively, which are valved at 64, 65, respectively. Conduits 22, 23 are valved at 67, 68 below the blowdown line connections. This provides a simple means for relieving the gas pressure in the upper portions of lines 22, 23. For example, tank 26 can be, in effect, disconnected from the system by closing valves 67, 70 and then opening valves 64, with a resultant escape of gas pressure in the upper part of line 22. Tank 25 can be disconnected in a similar manner by closing valves 68, 71 and opening valve 65.

Interior bulkhead 14 in Figures 1 and 2 is designed to withstand a small differential pressure only. The function of line 34 is to protect the interior bulkhead from rupturing due to excess differential pressure if the mud seal is lost. Normally the equalizer tanks take care of this but if the mud lines become plugged and pressure cannot be maintained on the seal because of slight leakage, it is evident that a pressure differential between stored gas and the drilling mud seal would quickly form. That is, if the gas pressure is unable to force mud down from the equalizer tank and mud was being lost, the pressure in the seal would drop below the pressure in the cavern. This invites a possible break-through of stored LPG. To avert this, valve 33 in line 34 will open when the gas pressure in the cavern exceeds the pressure in the seal chamber. Enough gas then flows through the valved lines into the seal chamber to balance the pressure on each side of the valve and, hence, on each side of the inner bulkhead 14. In this way line 34 serves as a safety feature.

The mud used in chamber 16 should be viscous but fairly fluid and should be a low water-loss type. A preferred composition is a bentonite-sodium carboxymethyl cellulose-water mixture having 6-8% by weight of bentonite (22 pounds/bbl.) and 1-3 pounds of sodium carboxymethyl cellulose/bbl. of total mud.

To illustrate the operation of the system assume that the product stored is propane (sp. gr.=.51), exerting a pressure of 150 p.s.i., and the heavy media fluid is 8.7# drilling mud with a specific gravity of 1.045. Assume the bulkheaded opening is 20 feet high and that the contact of propane and mud is 8 feet above the top of the

tunnel (Figure 2). If 150 p.s.i. is exerted by the propane at the top of the tunnel 10a, the pressure transferred through the top of the column 23 to the propane-mud interface will be reduced by about 1.8 p.s.i.

62.3×8×.51

and hence will be about 148.2 at this point. This pressure will be transferred to the mud and will be increased

10 by the weight of the mud downward in the column. Thus, at 8 feet down from the contact and at the top of the opening, the pressure will increase by 3.6 p.s.i. and will be 151.8 p.s.i. At 28 feet down from the contact and at the bottom of the bulkheaded opening, the pressure will increase by 12.7 p.s.i. and will be 160.9 p.s.i. These pressures will be transferred to similar locations within the seal chamber. Thus, at the top of the intermediate bulkhead 14 a pressure of 151.8 p.s.i. is exerted by the mud as against 150 p.s.i. of the propane; at the bottom 20 of the bulkhead the pressure of the mud will be 160.9 p.s.i. against the 154 p.s.i. exerted by the propane. Hence, the mud in chamber 16 tends to flow through the bulkhead into the tunnel. However, since it is too viscous to flow through the interstices, there will be no flow and a static condition will exist which will effectively seal the bulkhead.

It will be evident that the heavier the mud the greater the pressure differential across bulkhead 14. When the stored product is volatile, e.g. LPG, it is preferred to provide 30 vide heaters, such as electric heating elements 75, 76, on the lower portion of lines 22 and 23. In this way a column of vapor can be maintained in these lines, thus increasing the pressure differential between chamber 16 and the interior of the cavern.

35 The pressure exerted by the heavy media itself is constant and is only supplemented by the pressure exerted by the propane. Thus, the total pressure exerted on the heavy media within the seal chamber will always be in excess of the pressure of the propane. For example, 40 using the values just illustrated the pressure differential between the mud and propane at the top of the bulkhead (1.8 pounds) would be the same whether the pressure of the propane against the top of the bulkhead rose from 150 p.s.i. up to 200 p.s.i. or fell to 100 p.s.i. Similarly 45 the pressure differential at the base of the bulkhead would remain constant at 6.9 pounds. Therefore, the intermediate concrete bulkhead need only be designed for this pressure. However, as an added precaution against the rupturing of the intermediate bulkhead by a pressure 50 differential build-up due to some malfunction of the scheme, I provide the aforementioned direct connection between the propane side and the seal chamber, along with its check valve 33. Flow of propane into the void in the seal chamber will thus equalize the pressures at 55 any time when the mud exerts insufficient pressure to keep the check valve closed.

It is evident that other heavy media than mud having suitable viscosity and weight could be used in the seal chamber and that similar modifications could be made 60 at other points in the system without departing from the basic invention.

I claim:

1. In an underground storage system, in combination, an underground storage cavern, a tunnel connected to 65 said cavern, a pair of spaced fluid-tight barriers in said tunnel forming a seal chamber therein, a volatile liquid stored within said cavern under pressure, a viscous liquid immiscible with and having a greater specific gravity than the stored liquid occupying the chamber between the two 70 barriers, said latter viscous liquid exerting a pressure against the inner barrier which is greater than the opposing pressure thereon so as to prevent leakage through the tunnel from the cavern, means for admitting and withdrawing liquid from both the cavern and the chamber, 75 and pressure controlling means comprising a conduit hav-

ing one end connected with the interior of the cavern and the other end connected with the interior of the seal chamber and an intermediate portion thereof positioned above the level of the barriers and external thereto, whereby the two liquids form an interface within said intermediate portion of the conduit, the liquid above the interface being the stored fluid, thereby effecting a small pressure differential between the two liquids.

2. Apparatus of claim 1 wherein the interface is maintained above the level of the barriers, the weight of the intervening head of liquid providing the pressure differential between the cavern and the seal chamber.

3. In an underground storage system, in combination, an underground storage tunnel, a pair of spaced substantially water-tight concrete bulkheads in said tunnel, each sealing the tunnel from fluid flow therethrough, a volatile liquid storage within said tunnel under pressure, a viscous liquid immiscible with and having a greater specific gravity than the stored liquid occupying the chamber between the two bulkheads, said liquid exerting a pressure greater than that of the stored liquid and forming a liquid seal to prevent escape of stored product through the bulkhead, means for circulating the viscous liquid to maintain its density uniform, a tank positioned with its upper end above the upper level of the tunnel, a conduit extending from within the tunnel through said bulkheads to the top of said tank, said conduit being filled with stored fluid, and a second conduit extending from the base of the tank into the lower portion of said chamber and filled with said viscous liquid, the interface of the two fluids being within said tank, whereby the weight of the head of seal liquid between the interface and the top level of the tunnel is sufficient to maintain a pressure against the inner bulkhead in excess of the opposing pressure of the stored liquid.

4. The system of claim 3 wherein the means for circulating the seal liquid comprises a pump having a line extending into the upper portion of the seal chamber and a second line extending into the lower portion of the seal chamber, the operation of said pump serving to draw liquid from the lower portion of the chamber and to discharge it into the upper portion of the chamber.

5. Apparatus of claim 4 wherein the second line comprises means for introducing liquid thereto from an external source.

6. In the system of claim 3, a safety device to prevent possible failure of the inner bulkhead, said device comprising a line establishing communication between the stored liquid and the interior of the seal chamber, said line being provided with a valve which opens only to permit admission of stored liquid into said chamber, thereby permitting stored liquid to enter the seal chamber to equalize the pressure across the valve whenever the seal liquid exerts insufficient pressure to keep the valve closed.

7. In an underground storage system, in combination, an underground tunnel, a pair of spaced fluid-tight barriers in said tunnel arranged to seal same against fluid flow therethrough, a stored liquid contained on one side of said barriers, a seal liquid immiscible with the stored liquid occupying the space between the barriers, said seal liquid exerting a pressure against the inner barrier which is greater than the opposing pressure thereon so as to prevent leakage of stored liquid through the tunnel, and means for maintaining this pressure differential across the inner barrier which comprises a column of fluid having a greater specific gravity than the stored liquid, said column extending from the bottom of the space between said barriers to a point above this space thereby applying the head pressure of said column to said seal liquid, and conduit means supplying pressure communication from said stored liquid to the top of said column thereby applying pressure to the top of said column at least equal to the pressure at a point of corresponding level within said stored liquid.

8. In the system of claim 7, means for heating stored liquid into vapor in said conduit means thereby providing a vaporous medium to supply said pressure communication to the top of said column.

5 9. In the system of claim 7, a safety device to prevent possible failure of the inner barrier, said device comprising a line establishing communication between said stored liquid and the space between said barriers, said line being provided with a valve which opens only to permit admission of stored liquid into the space between said barriers, thereby permitting stored liquid to enter the space between said barriers to equalize the pressure across the valve whenever said seal liquid exerts insufficient pressure to keep the valve closed.

10 15. In an underground storage system the apparatus of claim 7, wherein the stored liquid is LPG and the seal liquid and fluid having a greater specific gravity than the stored liquid are a viscous fluid drilling mud.

10 20. 11. In an underground storage system, in combination, an underground tunnel, a pair of spaced substantially water-tight bulkheads in said tunnel, each bulkhead sealing the tunnel from fluid flow therethrough, a volatile liquid contained on one side of said bulkheads, a seal liquid immiscible with and having a greater specific gravity

25 than said volatile liquid occupying the space between the two bulkheads, said seal liquid exerting a pressure greater than that of said volatile liquid and forming a liquid seal to prevent escape of said volatile liquid through the bulkheads, a chamber positioned with its upper end above the upper level of the space between the bulkheads, a conduit extending from the volatile liquid contained by said bulkheads to the top of said chamber, said conduit being filled with said volatile liquid, and a second conduit extending from the base of said chamber into the

30 35. space between said bulkheads and filled with said seal liquid, the interface of the two liquids being within said chamber, whereby the weight of the head of seal liquid between the interface and the top level of the space between the bulkheads is sufficient to maintain a pressure against the inner bulkhead in excess of the opposing pressure of the contained volatile liquid.

40 35. 12. In an underground storage system, in combination, an underground storage cavern, a shaft extending from the surface of the earth to a point adjacent said cavern, a tunnel connecting said shaft with the base of said

45 50. cavern, a pair of spaced fluid-tight barriers in said tunnel forming a seal chamber therein, a volatile liquid stored within said cavern under pressure, a viscous liquid immiscible with and having a greater specific gravity than the stored liquid occupying the chamber between the two barriers, said latter viscous liquid exerting a pressure against the inner barrier which is greater than the opposing pressure thereon so as to prevent leakage through the tunnel from the cavern, means for admitting and withdrawing liquid from the cavern, and pressure controlling means comprising a conduit having one end connected with the interior of the cavern and the other end connected with the interior of the seal chamber and an intermediate portion thereof positioned above

55 60. the level of the barriers and external thereto, whereby the two liquids form an interface within said intermediate portion of the conduit, the liquid above the interface being the stored fluid, thereby effecting a small pressure differential between the two liquids.
